United States Patent Office.

ANDREW ANDERSON, OF MADISON, WISCONSIN.

Letters Patent No. 80,894, dated August 11, 1868.

IMPROVEMENT IN CLAMPS.

The Schedule referred to in these Letters Patent and making part of the same.

TO ALL WHOM IT MAY CONCERN:

Be it known that I, ANDREW ANDERSON, of Madison, in the county of Dane, and State of Wisconsin, have made new and useful Improvements in Self-Adjusting Clamps; and I do hereby declare the following to be a full, clear, and exact description of the nature, construction, and operation of the same, sufficient to enable one skilled in the art to which it appertains to construct and use the same, reference being had to the accompanying drawings, which are made part of this specification, and in which—

Figure 1 is a perspective elevation of the machine.

Figure 2 is a side sectional view of the same.

Figure 3 is an end sectional view.

The object of this invention is to provide a clamp which will, at one operation or movement of the hand, attach itself firmly to joists in buildings, ribs of ships, &c., and also press to its place the plank or flooring which is being laid, and hold it securely until it is spiked or nailed.

It consists of uniting together a pair of jaws, A, figs. 1 and 3, near their lower end, by means of hinges, toggle-joints, or other flexible devices, the upper ends of said jaws being made circular, as at B, fig. 2, and cam-shaped, as shown at C C, fig. 1, the cams commencing to curve outward at the inner surface of the jaws, at or near d d, fig. 1, and widening or separating from each other as the cam-ledge approaches the edge of the jaws at C C, fig. 1.

It further consists in the application of a lever, E, figs. 1, 2, and 3, in such a manner as to cause, by swinging the upper end of the lever forward and backward, an opening and closing movement of each end of the jaws, and to force forward and backward by the same movement a plunger, F, figs. 1 and 2.

The plunger is a straight piece of iron or wood, provided with a cross-piece at its outer end, and slotted upon each edge, (O, fig. 2,) near the cross-piece. It is attached to the lever at P, fig. 2, and slides upon the two pins r r, fig. 3, projecting from the inner face of the jaws. The lever is suspended between the jaws by a pin or bolt, G, fig. 2, at a point which is the centre of an arc of a circle, shown at the top of the jaws in fig. 2.

At a point upon the lever even with the top of the jaws, a yoke, H H, fig. 3, is secured to the lever, its ends being provided with bosses projecting downwards, i i, and its centre with another, j, fig. 3.

These bosses, enclosing the cam-ledge out and inside, serve to control the jaws, and cause the motion of the same to and from each other at their ends, when the lever is operated forward and backward.

The lower ends, K, fig. 2, of the jaws are provided with spikes, L L L, fig. 2, which penetrate the joist M, fig. 1, when the lever is pressed back to an upright position, (as in fig. 1,) and prevents the jaws from slipping when the plunger is brought against the floor-board or plank to be operated upon.

To operate the machine, place it astride the joist M, figs. 1 and 3, with the handle or lever in the position shown in fig. 2, and the cross-piece of the plunger close to the board to be operated upon; then press the handle backward nearly or quite into the position shown in fig. 1, as may be found necessary to bring the board to a tight joint where it is to be nailed.

To remove the clamp, pull the handle forward, when it will release the board from pressure and itself from the joist, and may be removed.

A pawl or hand may be attached to the handle in such manner as to catch into teeth or cogs cut into the periphery of the cams, and hold the handle in the position to which it has been brought (in forcing the board to a joint) while nailing.

The clamp may be set to any thickness of joist by moving the nuts S S, figs. 1, 2, and 3.

Having described my invention, what I claim as new, and desire to secure by Letters Patent, is—

The combination of the cams C C, the jaws A A, the lever E, the yoke H H, and the plunger F, all constructed, arranged, and operating as and for the purposes herein set forth.

ANDREW ANDERSON.
